INVENTOR:
OLE K. BAKKEN.
By Whitley and Ruckman
ATTORNEYS.

Patented Apr. 24, 1923.

UNITED STATES PATENT OFFICE.

OLE K. BAKKEN, OF NORTHWOOD, NORTH DAKOTA.

STATION SELECTOR.

Application filed January 30, 1920. Serial No. 355,289.

To all whom it may concern:

Be it known that I, OLE K. BAKKEN, a citizen of the United States, residing at Northwood, in the county of Grand Forks 5 and State of North Dakota, have invented certain new and useful Improvements in Station Selectors, of which the following is a specification.

My invention relates to station selectors 10 and particularly to a selective ringing device for party line exchanges. This application is a continuation in part of my prior application, Serial No. 189,220, filed August 31, 1917. The principal objects of my 15 invention are as follows: To provide means whereby a signal may be operated at any desired instrument for a party communication line without operating the signal of other instruments of the line; to provide means 20 which will eliminate the attendant evils such as listening which accompany the simultaneous ringing of all signals on a party line; to render available the advantages of a private line while avoiding the multiplicity of 25 main line wires; in general to improve the form of telephonic communication on party lines by providing selecting means which enables an operator to signal and communicate with anyone of the party instruments 30 on a party line without signaling other instruments of this line.

The full objects of my invention will appear in connection with the detailed description thereof and the novel features embodied in my inventive idea will be particularly pointed out in the claim.

In the accompanying drawings which illustrate the application of my invention in one form,—

Fig. 1 is a diagrammatic view showing the ratchet wheel in its normal position. Fig. 2 is a diagrammatic view showing the ratchet wheel after it has been operated three times. Fig. 3 is a diagrammatic view 45 showing the ratchet wheel released and returned to normal position. Fig. 4 is an edge view of the ratchet wheel and pawl.

The drawings show my improved device as it is installed in one of the houses on the 50 party line and it is not necessary to show the installation for each of the houses on the line, since the device is the same for all of them except that for each house the device is set for the particular number assigned to that house. Upon a board 10 there is mounted a segmental ratchet wheel 55

12 which is capable of partial rotation upon a spindle 14, the normal position of the ratchet wheel being determined by a pin 16 carried by the board 10. The ratchet wheel 60 normally occupies the position shown in Fig. 1 with its right hand portion in engagement with the stop 16. The ratchet wheel is provided with a plurality of teeth 65 consecutively numbered to correspond with the numbers assigned to the different houses, and, as shown in the drawings, these numbers range from 1 to 14, thus providing for a fourteen-party line. Mounted upon the board 10 is a polarized electro magnet 18 70 of well known construction which is affected only by a relatively high tension current. This high tension current may be produced by a magneto which supplies a slowly alternating current. Such magnetos are well 75 known and do not need to be described for a full understanding of my improved features of construction. The electro magnet 18 is provided with an armature 20 which carries a bar 22, to the lower end of which is pivoted an arm 24 provided with a pawl 26 80 adapted to engage the teeth of the ratchet wheel 20 and turn the same the space of one tooth at a time. The outer end of the arm 24 is attached to a link 28. The arm 24 85 extends through a slot in the link 28 so that the pawl 26 may move from tooth to tooth without moving the link. One end of this link is connected to a detent 30 by a pin and slot connection, and the other end of 90 the link is pivoted to the lower end of an armature 32 associated with an electro magnet 34. This electro magnet is of well known construction so wound as to be affected only by a relatively low tension current. The 95 ratchet wheel 12 carries an arm 36 which may be set to correspond with the number assigned to any particular house, and in the drawings it is shown set for No. 3. When the device is thus set and it is desired 100 to call this number from the central station three impulses of an alternating current are sent through the main line and these impulses cause the pawl 26 to operate three times and bring the ratchet wheel to 105 the position shown in Fig. 2 so that the arm 36 engages a bow 38 and moves the same into engagement with a stop post 40. It is obvious that the ratchet wheel at the place 110 which is called may be readily moved the desired number of times since it is operated by a slowly alternating current and the op-

erator observes the movement of one of the ratchet wheels at the place from which he is signaling. Although the ratchet wheels at all of the houses on the houses on the line 5 will be actuated three times the one set for the No. 3 is the only one in which the bow 38 will be retained in contact with the post 40. After this has been done the operator at the central station pushes a button and 10 sends a direct current through all of the electro magnets 34. The armatures 32 are thereby attracted, but, as will be apparent from Fig. 1, all of these armatures except the one on the device set for the No. 3 will 15 pass the end of the bow 38 since only this one bow has at this time an engagement in raised position with the post 40. When the armatures 32 are attracted it will be seen from Fig. 3 that all of the pawls 26 and de- 20 tents 30 are pulled up from engagement with the ratchet wheels so that all of the ratchet wheels are free to return to their initial or zero position. At the same time the direct current from the central station rings 25 the bell 42 at the house numbered 3, since a circuit is provided by means of a path for current extending through the bow 38 and the insulated wire 43 when the parts are in the position shown in Fig. 3. The wire 43 30 extends from the bell to an insulated contact point in the lower end of the armature. In order that a person at any house may be able to call "Central" I provide a local battery 44 in a shunt circuit adapted to be 35 closed by a push button 46 which is secured to a spring member 47 connected to the wire 48 forming part of the main circuit so that upon pushing the button the circuit from the battery 44 is completed and a signal is 40 operated at the central station when the device is in normal position. The member 47 is resilient and is fixed at its upper end while its lower end carries a contact 49 which normally engages a fixed contact 50. The re- 45 siliency of the member 47 is sufficient to maintain the contact 49 in circuit closing engagement with the contact 50. The button 46 is secured to the member 47 and passes through the same and when this button is 50 pushed the circuit through the members 49 and 50 is broken and the inner end or stem of the button engages a contact connected with one side of the battery so that the lat-

ter is placed in the circuit which goes to the central station.

While my device has been described in connection with a central station it is obvious that the same construction may be employed in a system in which the device at any house is used in directly calling any other house on the party line without the necessity of first calling central. In this case a generator is used at each house which will send alternating current through the electro magnet 18 and cause the wheel 12 to 60 be moved one tooth at a time until the desired number is reached. It will be understood that the arm 33 is set for different positions at each of the houses on the line, the position for each house corresponding to 65 the number varying from one to fourteen which is given to the house. It is not necessary to show the generator which is used, since this might obviously be the well known magneto previously referred to which supplies a slow alternating high tension current.

I claim:

A selective signaling device for party lines comprising signaling means, a ratchet wheel, an arm adapted to be fixed in different positions on said ratchet wheel, a pawl engaging said ratchet wheel, a stationary electro magnet, connections between said pawl and the armature of said electro magnet whereby successive electrical impulses move said ratchet wheel progressively, a pivoted bow-shaped member normally in inoperative position and adapted to be moved by said arm into circuit-making position for operating said signaling means, a second stationary and independent electro magnet having an armature adapted to be moved by an electrical impulse into contact with said bow-shaped member to complete 80 a circuit through said signaling means, a detent for said ratchet wheel, and a link connecting said second mentioned armature with said pawl and said detent whereby said pawl and said detent are both lifted away 85 from said ratchet wheel when said second mentioned armature is attracted.

In testimony whereof I hereunto affix my signature.

OLE K. BAKKEN.
